CLAIM

The ornamental design for a dual opening lid for a drink container as shown and described.

DESCRIPTION

FIG. 1 is a left, front isometric view of a dual opening lid for a container showing my new design.

FIG. 2 is a right, front isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings illustrate portions of the dual opening lid for a drink container that form no part of the claimed design.

FIG. 1

FIG. 2

FIG. 3

FIG. 4

FIG. 5
